BENJAMIN BRODO Inventor

By His Attorney O. V. Thiele

UNITED STATES PATENT OFFICE.

BENJAMIN BRODIO, OF NEW YORK, N. Y., ASSIGNOR TO LOCOMOTIVE SUPERHEATER COMPANY, OF NEW YORK, N. Y., A CORPORATION OF DELAWARE.

BOILER WITH SUPERHEATER.

1,351,154.

Specification of Letters Patent. Patented Aug. 31, 1920.

Application filed January 24, 1918. Serial No. 213,514.

To all whom it may concern:

Be it known that I, BENJAMIN BRODIO, a citizen of the United States, residing at New York, N. Y., have invented certain new and useful Improvements in Boilers with Superheaters, of which the following is a specification.

My invention relates to boilers of the type having horizontal or slightly inclined water tubes connecting front and rear water legs, and a furnace bounded by a bridge-wall at the rear leaving some space between the bridge-wall and the rear wall of the boiler setting. The object of my invention is to provide an arrangement wherein the superheater is placed in a position where the gases coming into contact with it reach it while they are at a high temperature; wherein the superheater is protected from the direct radiant heat from the furnace; wherein the relative portion of the gases passing over the superheater may be readily regulated by means at a point remote from the hottest part of the passage; wherein the passage for the gases leading over the boiler tubes is not restricted as compared with boilers of this type without superheaters; wherein the superheater shall be accessible for inspection and repairs, and its individual units be readily removable; which shall permit of ready cleaning; and which may be installed without practically any re-design or re-arrangement of the boiler itself. Other objects will become evident from the description that follows:

The specification is to be read in connection with the accompanying drawings, in which Figure 1 shows a longitudinal section of a boiler according to my invention; Fig. 2 as a fragmentary section on line 2—2 of Fig. 1; Figs. 3 and 4 are sections, similar to Fig. 1, of modifications, with parts broken away in Fig. 4.

The water-tubes 1 of the boiler connect front and rear water-legs 2 and 3, these legs communicating with the steam and water drum 4. The furnace 5 is bounded at the front by the wall 6 and at the rear by the bridge-wall 7. Three horizontal baffles, 8, 9, and 10, direct the course of the gases over the water tubes, delivering them finally to flue 22, which communicates with the stack.

The superheater is placed, in my arrangement, into the space behind the bridge-wall. In the form shown in Figs. 1 and 2, the

superheater consists of the headers 11 and 12, connected to which are the superheater units 13. The units are secured to the headers by means of the familiar clamp and bolt arrangement. The headers are located in 60 the side wall 14, where they are out of the hot current of gases, and are accessible. The units are looped, as is clearly shown in Fig. 2, and extend transversely across the space behind the bridge-wall. The pipe 15 65 delivers steam from the drum 4 to the header 11, and pipe 16 carries it away from header 12.

Baffle 8 extends from the front water leg 2 to a point some distance from the rear water leg 3. This baffle is shown located above some of the boiler tubes.

The baffle 10 also extends from the front water leg to a point at some distance from the rear water leg. It is located at or near 75 the top of the entire bank of water tubes.

Between the two is located the baffle 9. It does not extend entirely to the front water leg, but terminates short of it, leaving a passage for the gases between its end and the front water leg. Instead of extending entirely to the rear water leg, which is the customary arrangement in this form of baffling, this middle baffle extends only to a point at some distance from this leg, and from its 80 rear end a baffle 17 extends down, parallel to the water legs, forming a passage 18. This baffle is continued downward, dividing the space between the bridge-wall 7 and the rear boiler wall into two chambers, and terminates some distance above the bottom of the setting. About half the superheater units are located in one of the two chambers and half in the other.

At a point in the passage 18 below the 95 boiler tubes but above the superheater units I arrange the damper 19, capable of partly or wholly closing the passage. An opening 20, closed by a door 21, is placed in the rear wall above the damper 19. The lower wall 100 of this opening and the damper in its closed position will be observed to form a continuous, outwardly sloping surface.

It will be noted that the arrangement described provides a double passage for the 10 gases of combustion. A portion of them after leaving the firebox and passing over the bridge-wall flow upward, through the passage between the baffles 8 and 9, around the front end of baffle 9, back through the 110

passage between baffles 9 and 10, and up to flue 22. Another portion, after passing over the bridge-wall 7, flows downward over the first half of the superheater units, 5 around the lower end of baffle 17, then upward over the remaining half of the superheater units, and up through passage 18 joining the first portion of the gases and being delivered together with them to 10 flue 22.

The proportions of the boiler and superheater, and the normal distribution of the products of combustion between them are such that the two currents of gases at the 15 point where they rejoin each other are of substantially the same temperature. Should this not be the case, or should it be desired to raise or lower the degree of superheat given the steam, proper adjustment can be made 20 by means of damper 19. The path over the superheater, it may be pointed out, is shorter than that over the water tubes, and there is no difficulty in getting a portion of the gases to take it in preference to the longer path, 25 while at the same time the path over the water tubes is not in any way restricted.

The advantage of my arrangement on the score of cleaning should be noted. Any accumulations of ashes, etc., on baffles 9 and 30 10 can be blown toward the rear and allowed to pass down through passage 18 and out through opening 20, their falling on the superheater being prevented by damper 19, put into its closed position for this purpose. 35 From baffle 8 such accumulations can also be removed toward the rear, and allowed to fall between the superheater units into the space below the superheater, whence they may be removed through a door in the 40 setting.

It will be clear that the precise form of the superheater does not enter into my invention, but that it may be given any suitable form. Instead of being made up of loops, 45 it may, for example, be made up of straight pipes. If made up of loops they may be variously arranged. They might, instead of lying transversely, run lengthwise, or vertically. Two forms in which they are 50 arranged vertically are shown in Figs. 3 and 4. In the former the headers, 11 and 12, are placed in the rear wall and the units are made up of loops half of which are located behind baffle 17, and half before it.

55 The boiler baffling in this case differs somewhat from that of Fig. 1. There are only two baffles, the location and extent of the lower one 8^1 , being the same as that of the lower one, 8, of Fig. 1; and the other 60 one, 9^1 , being located at the top of the bank of tubes, its extent corresponding to that of baffle 9 of Fig. 1. The rear end of baffle 9^1 joins with baffle 17.

In the form of Fig. 4 the loops of the 65 units are all placed in front of baffle 17

which is here moved closer to the rear wall of the setting. The headers 11 and 12 are shown to run across the boiler, though they may evidently be arranged otherwise. Likewise, it will be clear, the units may here 70 have loops extending in some other direction than vertical. I show here a baffle 23 extending rearwardly from the upper end of the bridge-wall and terminating some distance from baffle 17. Its purpose is to 75 protect the units somewhat from the intense furnace heat, and this feature may evidently, if desired, also be embodied in the other arrangements shown.

The action of the forms illustrated in 80 Figs. 3 and 4 are obvious, and require no further description.

In each of the arrangements described I attain the advantages above enumerated. Many variations may evidently be made 85 without losing the essential features of my invention, and such variations I regard as forming part of my invention.

What I claim is:

1. In a boiler comprising a front and a 90 rear water leg, horizontal parallel rows of water tubes connecting them, and a furnace under the tubes bounded at the rear by a bridge-wall, the combination of a baffle between two rows of tubes but terminating 95 short of each water-leg, a partition extending downwardly from the rear end of the baffle into the space behind the bridge-wall and terminating short of the bottom of the setting, a second baffle below and parallel 100 to the first extending from the front water leg and terminating short of the partition, and a superheater behind the bridge-wall.

2. In a boiler comprising a front and a 105 rear water leg, horizontal parallel rows of water tubes connecting them, and a furnace under the tubes bounded at the rear by a bridge-wall, the combination of a baffle between two rows of tubes but terminating short of each water-leg, a partition extending downwardly from the rear end of the baffle into the space behind the bridge-wall and terminating short of the bottom of the setting, a second baffle below and parallel 110 to the first extending from the front water leg and terminating short of the partition, and a superheater, some of the elements of 115 which are located between the bridge-wall and the partition.

3. In a boiler comprising a front and a 120 rear water leg, a bank of water tubes connecting them, and a furnace under the tubes bounded at the rear by a bridge-wall, the combination of a baffle near the bottom of the bank of tubes and extending from the 125 front water leg inward, a second baffle near the top of the bank extending from the front leg inward, a third baffle between the other two terminating short of both water legs, a partition extending downward from 130

the rear end of the third named baffle into the space behind the bridge-wall; by which arrangement two passages are formed for the hot gases, dividing just beyond the 5 bridge-wall and reuniting just as the gases leave the water tubes; and a superheater behind the bridge-wall.

4. In apparatus of the class described, the combination of a front header, a rear header, 10 water tubes connecting them, a superheater, a furnace, and means to expose a portion of each of the tubes to gases directly from the furnace, and the remaining portion only to

gases from the furnace that have passed over the superheater but over substantially no 15 boiler surface.

5. In apparatus of the class described, the combination of a water leg, a partition spaced from it, a superheater, a furnace, and means to direct only gases from the furnace 20 that have passed over the superheater but over substantially no boiler surface through the space between the partition and the water leg.

BENJAMIN BRODIO.
